ARTIFICIAL CHRISTMAS TREE

Mason J. Curtiss, 208 Breakspear Road, Syracuse, N.Y.

Filed Dec. 2, 1958, Ser. No. 53,616

Term of patent 14 years

(Cl. D29—1)

FIG. 1—

FIG. 2

Figure 1 is a front elevational view of an artificial Christmas tree, showing my new design.

Figure 2 is a side elevational view thereof.

The design is characterized by the relatively shallow curved loops with the extending portions of each loop being in substantially close relationship to the next adjacent portion all as shown.

I claim:

The ornamental design for an artificial Christmas tree, as shown and described.
